(57) **CLAIM**

The ornamental design for an electronic device with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of an electronic device with graphical user interface, showing just the graphical user interface of FIG. 3 applied to a display screen or portion thereof; FIG. 2 is a second embodiment thereof; and, FIG. 3 is a front view of an electronic device with graphical user interface. The graphical user interface design of FIG. 2 may be similarly applied thereto.

The broken lines in FIGS. 1 and 2 show a display screen or portion thereof, and form no part of the claimed design. The broken lines in FIG. 3 show an electronic device having a display screen, and form no part of the claimed design.
